CLAIM

The ornamental design for a combined pen and caliper, as shown and described.

DESCRIPTION

FIG. 1 is a front elevational view of a combined pen and caliper showing my new design;

FIG. 2 is a right side elevational view, the left side being a mirror image thereof;

FIG. 3 is a top plan view thereof;

FIG. 4 is a bottom plan view thereof;

FIG. 5 is a rear elevational view thereof in an exploded condition;

FIG. 6 is a rear elevational view with the cap member removed for convenience of illustration;

FIG. 7 is a top plan view of FIG. 6 with the caliper extensions in a closed position; and,

FIG. 8 is a top plan view of FIG. 6.

FIG. 1

FIG. 2

FIG. 5

FIG. 6

FIG. 3

FIG. 4

FIG. 7

FIG. 8
